UNITED STATES PATENT OFFICE

2,060,895

HOSIERY DRYING APPARATUS

Thomas W. Prosser and John H. Wahlbeck, Kankakee, Ill., assignors to Paramount Textile Machinery Co., Chicago, Ill., a corporation of Illinois

Application April 26, 1933, Serial No. 667,980

2 Claims. (Cl. 223—76)

Our invention relates to hosiery drying forms of the type which are mounted upon a conduit or pipe which supplies a heating medium, such as steam or hot water, to the interior of the form, and is concerned more particularly with an arrangement for detachably securing the form to the conduit so as to facilitate the interchangeability of the forms on the same or on other conduits and of permitting the mounting of a plurality of different sizes and shapes of forms on the same conduit.

The form contemplated by the present application is of the general type disclosed in United States Letters Patent to Butz, No. 1,207,496, dated December 5, 1916. Forms of this character are commonly bolted to a conduit or pipe which supplies the heating medium to the interior of the form, each form being intended to dry and shape a particular size and style of stocking. A hosiery mill, however, manufactures many different shapes and sizes of hosiery, so that it has heretofore been necessary to provide separate drying tables carrying the required styles and shapes of forms, or to actually unbolt one style of forms for replacement by another on the conduits, an exceptionally slow and uneconomical operation, or to provide attachments which resiliently grip the sides of the form and which are utilized to vary the size and shape of the drying form. The latter expedient, in particular has been found to be highly objectionable because of the tendency of the attachments to split along their welded joints, resulting in rough edges which snag or tear the stocking. Moreover, these attachments are rather expensive to make and maintain, and they are easily battered in handling.

It is therefore one of the principal objects of our invention to devise a mode of connection between the drying form and conduit which takes the form of a coupling connection, one part of which is carried by the form and the other part permanently fastened to the conduit, securing devices being provided to detachably connect these coupling parts together and so mount the drying form on the conduit.

A further object is to provide a coupling connection in which the coupling part that is secured to the drying form is standard for all forms, regardless of their size and shape, so that, in a drying room so equipped, a form may be quickly attached or detached to or from any conduit, or to or from any point along any particular conduit.

A further object is to provide a coupling connection of the character indicated which is constructed and arranged to permit a limited shifting of the form rotarily of its longitudinal axis for the purpose of placing the form in a selected position most convenient for the boarding operator.

These and further objects of our invention will be set forth in the following specification, reference being had to the accompanying drawings, and the novel means by which said objects are effectuated will be definitely pointed out in the claims.

In the drawings:

Fig. 1 is an elevation of a hosiery drying form showing our improved coupling connection interposed therebetween and the conduit which supplies heating medium to the drying form.

Fig. 2 is a sectional elevation taken along the line 2—2 in Fig. 1, looking in the direction of the arrows.

Fig. 3 is an enlarged sectional elevation of the coupling connection and the associated conduit and form, as viewed in Fig. 1.

Fig. 4 is a section along the line 4—4 in Fig. 3, looking in the direction of the arrows.

Fig. 5 is a view similar to Fig. 4, but showing the form shifted rotarily around its axis of support on the conduit.

Fig. 6 is a view similar to the lower portion of Fig. 1, showing a modified type of coupling connection.

Fig. 7 is a section along the line 7—7 in Fig. 6, looking in the direction of the arrows, and showing in dotted lines an alternative position of the drying form.

Fig. 8 is a view, partly in section, similar to that shown in Fig. 6, but illustrating a further modification of the coupling connection.

Fig. 9 is a section along the line 9—9 in Fig. 8, looking in the direction of the arrows.

Figs. 10 and 11 are elevation and plan views of a modified type of clamping mechanism which may be employed in connection with the coupling connections shown in Figs. 3 and 6.

Figs. 12 and 13 are elevation and plan views, respectively, showing still further modifications of clamping mechanisms which may also be employed in connection with the coupling connections shown in Figs. 3 and 6.

Referring to Figs. 1 to 5, inclusive, the numeral 1 designates a hosiery drying form of a type well known in the industry, the precise size and shape of which is immaterial for present purposes, but which is hollow for the purpose of receiving a

45

50

55

heating medium and preferably is divided into two communicating chambers by a longitudinally extending septum 2. Further, in connection with the type of form employed, it will be understood that the essential features of our invention are not restricted to a form which is heated internally by steam or hot water, since our coupling connection is also adaptable for use with electrically heated forms, as well as those of the externally heated type. The primary purpose of our invention is to permit easy and rapid interchangeability of forms on the same supporting structure, so that the nature of the heating medium is wholly immaterial.

15 The base of the form is provided with the customary flange 3 having bolt holes 4 through which extend studs 5, whose lower ends are threaded in a form-attaching part 6 that constitutes one of the portions of the coupling connection. Nuts 7 are threaded on the upper ends of the studs 5 serve to clamp the indicated parts together and a gasket 8 of suitable material may be interposed between the flange 3 and the coupling part 6. The coupling part 6 is provided with a passage 9 for 20 delivering steam, for example, to a chamber 10, located to the left of the septum 2, while the same passage communicates with the chamber 11 on the opposite side of the septum by means of a connecting passage 12.

30 The underside of the coupling part 6 is provided with a boss 13 which is separated from a similar boss 14 that extends upwardly from a coupling part 15 by an appropriate gasket 16. Securing studs 17 pass through suitable apertures 35 in the coupling part 15 and their lower ends are threaded in the wall of a conduit 18, nuts 19 threaded on the upper ends of said studs serving to permanently retain the part 15 in position on the conduit. A suitable sealing gasket 20 may be 40 interposed between the part 15 and the conduit 18. In order to facilitate a proper seal between the conduit and the part 15, the under surface of the latter is preferably shaped to fit the curvature of the conduit, as indicated by the numeral 21 in 45 Fig. 2.

The coupling part 15 is also provided with a passage 22 which is in alignment with the passage 9 and also with an aperture 23, of which there are two shown in Fig. 3 corresponding to the 50 usual pair of such openings found in steam conduits that support drying forms, but only one of which is required in the present instance, the other aperture being sealed by the gasket 20. Extending upwardly within the passage 22 is a 55 steam nozzle 24 whose lower end is threaded within a steam pipe 25 which is in communication with a suitable steam supply. Under these conditions, therefore, steam passing through the pipe 25 is delivered through the nozzle 24 to the 60 passage 9 and then upwardly through the chamber 10 in the form and thence downwardly through the chamber 11 for final exhausting through the passages 12 and 9, respectively, and final delivery into the conduit 18.

65 In the type of connection shown in Fig. 3, the following instrumentalities are employed to detachably secure the coupling parts together. In one end of the coupling part 15 there is threaded the lower end of a bolt 26 whose shank extends 70 upwardly through the bifurcated end 27 of the coupling part 6, the head of the bolt resting on the top surface of the indicated end of the coupling part. The spacing of the bolt head from the part 15 may be adjusted as desired and there- 75 after maintained in this position by a lock nut 28.

At the opposite end of the coupling part 15 is provided an ear 29 having threaded holes 30 and 31 extending inwardly from the opposite faces thereof and with their axes angularly disposed to each other, as clearly shown in Figs. 4 and 5, the axis of the threaded hole 30 being normally disposed with respect to the axis of the conduit 18. In the position of the form shown in Fig. 4, a screw 32 is mounted in the hole 30 and upon this screw is journaled the lower end of an eye bolt 33 whose shank extends upwardly through the bifurcated end 34 of the coupling part 6 and mounted on the upper extremity of the shank 33 is a hand wheel 35 which is preferably composed of a suitable non-conducting material for the purpose of protecting the hand of the operator when it is necessary to change the form. The top surfaces of the bifurcated end 34 slope downwardly from the form in order to accommodate the angularity of the eye bolt shank 33 and a shoulder 36 is formed at each end of the bifurcated portion, so that when the hand wheel is screwed down tightly to clamp the coupling part 6 to the coupling part 15, there will not be any possibility of the bolt sliding off the bifurcated end.

In mounting the form on the conduit, it is only necessary to insert the bifurcated end 27 under the head of the bolt 26 and rest the boss 13 on the gasket 16. The hand wheel 35, which is then occupying a position displaced from that shown in Fig. 3, is then swung upwardly to the position shown in Fig. 3 and clamping pressure applied to the upper surfaces of the bifurcated end 34. During this action, it will be obvious that the head of the bolt 26 acts as a fulcrum, so that a very effective pressure can be applied to the gasket 16 to thoroughly seal the coupling connection in this location by reason of the lever action of the coupling part 6 under the pressure applied by the hand wheel 35.

In order to maintain the hand wheel 35 free of contact with the conduit 18 when swung outwardly to permit the removal of a form, the lower end of the bolt may be provided with a flat surface 37 for engaging with the vertical surface 38 on the coupling part 15, these two parts engaging to limit the downward swinging movement of the bolt.

For reasons set forth in United States Letters Patent to Prosser, No. 1,816,296, dated July 28, 1931, it is frequently desirable to shift the form from the position shown in Fig. 4 to the angular position shown in Fig. 5. Generally speaking, the purpose of this shifting of the form is to facilitate the boarding and stripping of the stocking, since the operator who faces the form is better able to place the hands on opposite sides of the form in order to grasp the stocking. Our improved coupling connection is readily adaptable for this purpose, since it is only necessary to provide an additional threaded hole 39 in the coupling part 15, this hole corresponding to the hole 40 which receives the lower end of the bolt 26. To shift the form to the position shown in Fig. 65 5, it is merely necessary to remove the screw 32 from the hole 30 and mount it in the angularly disposed hole 31. The pivot of the bolt 33 is accordingly shifted to the opposite side of the lug 29 and on the opposite side of the form, the bolt 70 26 may be shifted from the hole 40 to the hole 39. Accordingly, a drying form provided with a single type of coupling part 6 may be located in either of the drying positions on a conduit shown in Figs. 4 and 5.

The modification illustrated in Figs. 6 and 7 differs essentially from that just described in that instead of providing for shifts of position of the drying form by relocating the bolt elements in the lower coupling part, the upper coupling part is provided with additional means for engaging the bolts which remain fixed in position.

Accordingly, the numeral 41 designates the lower coupling part which is mounted on the conduit 10 and which corresponds generally to the coupling part 15, except that additional mountings for the bolts are not provided. At the opposite ends of the coupling part 41 are mounted the fixed bolt 42 and the swinging bolt 43, corresponding to the 15 same parts illustrated in Fig. 3, and which, when the drying form is occupying a position which is aligned with a vertical plane passing through the conduit, for example, extend upwardly through slots 44 and 45, respectively, provided in the opposite ends of the upper coupling part 46. To provide for rotarily shifting this form, the coupling part 46 is provided with additional slots 47 and 48 which are angularly displaced with respect to the slots 44 and 45, respectively, so that when the 20 bolts 42 and 43 are occupying the slots 47 and 48, the drying form will occupy the shifted position shown in dotted lines in Fig. 7.

In the modification shown in Figs. 8 and 9, the drying form 49 is not of the standard type corresponding to that heretofore described, but is provided with a downwardly extending shell 50 having flanges 51 which extend in opposite directions from the shell. The lower end of the shell 50 projects below the flanges 51 and is journaled 35 within a hole 52 provided in a lower coupling part 53. The part 53 is attached to a conduit 54, corresponding to the conduit 18 by means of studs 55 which pass through the part 53 for threaded reception in the wall of the conduit 54. A gasket 56 is interposed between the part 53 and the conduit 54. The studs 55 are locked in position by means of nuts 57 which also serve to hold the coupling part 53 against the gasket and said studs extend upwardly through open ended, curved 40 slots 58 provided in the flanges 51 which constitute the upper coupling part. Wing nuts 59 threaded on the upper ends of these studs 55 are utilized to press the coupling part 51 downwardly into firm contact with a gasket 60, similar to the 45 gasket 16, which is interposed between the two coupling parts.

Internally, the shell 50 is divided into inlet and exhaust passages 61 and 62, respectively, by a septum 63 and projecting upwardly into the passage 61 is a steam nozzle 64 whose lower end projects through an aperture 65 provided in the wall of the conduit 54 for support upon and communicating relation with a steam pipe 66. Exhaust steam passing downwardly through the 50 passage 62 is delivered to the conduit 54 through an aperture 67.

Within the length of the curved slot 58, it will be obvious that the form 49 may be rotarily shifted into a plurality of positions and in each 55 of these positions, operative connection with the conduit 54 may be established by applying suitable pressure through the medium of the wing nuts 59. To remove a form, it is merely necessary to loosen these nuts and rotate the form until the curved slots are clear of the studs 55, whereupon the form may be simply lifted from the conduit.

In Figs. 10 and 11 is illustrated a modified form of clamping member which may be substituted for the swinging bolts 33 or 43 shown in

Figs. 3 and 6, respectively. In this modification, the numeral 68 designates a swinging bolt of the general type heretofore described and upon which is mounted a cam member 69 that is freely rotatable upon the shank of the bolt and which may be moved to any desired position by means of a handle 70. Above the cam member, a special nut 71 is threaded on the shank of the swinging bolt and this nut is provided with a depending finger 72 which is intended to engage 10 with a helical cam surface 73 on the cam member. A lock nut 74 maintains the nut 71 in any adjusted position. If it is considered that this locking modification is employed as a substitute for the swinging bolt 33, the underside of the 15 cam member 69 will engage the upper surfaces of the bifurcated ends of the upper coupling part 6 when the drying form is in operative position. At this time, the cam 65 will occupy the position substantially shown in Fig. 10. In order to loosen 20 the clamp to permit removal of the form, it is merely necessary to rotate the handle 70 in a clockwise direction, as viewed in Fig. 11, to thereby free the finger 72 from contact with the cam surface 73, whereupon the cam may be shifted 25 upwardly along the shank of the bolt and the latter swung toward the right to a position free of the part 6. In mounting the form with this clamping modification, it will be obvious that a 30 reverse movement of the handle 70 will bring 30 the cam surface to engagement with the finger 72 until the desired pressure is obtained.

In Figs. 12 and 13 is illustrated a still further form of clamping device which is shown in connection with the coupling connection illustrated 35 in Fig. 3, more particularly, but which is also susceptible of use for the coupling connection illustrated in Fig. 6. In this modification, the numeral 75 designates a pair of link members whose lower ends are pivotally connected to the 40 ear 29, for example, on the coupling part 15. The upper ends of these links are pivotally connected to a cylindrical cam 76, the pivot connection being eccentric with respect to the axis of the cam, as clearly shown in Fig. 12. An operating handle 77 projects from one side of the cam 76 and is preferably composed of a material that does not readily conduct heat. From an examination of Fig. 12, it will be obvious that, by rotating the handle 77 in a clockwise direction, the cam 76 45 will be moved to a position permitting a swinging of the links 75 toward the right and therefore a separation of the coupling parts. When swung in the opposite direction, with the coupling parts in the positions shown, pressure is applied 50 to the upper coupling part 6 in a manner to operatively seat the drying form on the lower coupling part.

From the foregoing description, it is apparent that, in any of the modifications illustrated, any 55 type of form, regardless of shape, style or size, may be interchangeably fitted to the lower coupling parts which are mounted on the conduit. Our improved coupling connection therefore provides a simple arrangement for standardizing the 60 forms as regards their capacity for attachment to a plurality of conduits and accordingly renders more flexible the manufacturing program of a hosiery mill. Those forms which are not in use 65 may be stored on the wall in appropriate racks, or on racks built in the form of a truck which may be moved from place to place dependent upon the demands of production. Accordingly, even though the mill is provided with a limited 70 supply of drying tables, a variety in the hosiery 75

production may be obtained on any day or on successive days merely by changing the forms from time to time as circumstances require. The nature of our coupling connection permits these changes to be made very rapidly and with a minimum of loss in production time.

5 We claim:

1. In a hosiery drying structure, a coupling device for facilitating the rapid attachment and detachment to and from a heat supplying conduit of a hosiery drying form having a base flange normally intended to be directly attached to a conduit, comprising a pair of elongated coupling parts, one of the parts being permanently fastened to the wall of the conduit and the other part adapted to be permanently secured to the flange and including a pair of open ended slots at each end thereof arranged to provide cooperative pairs at opposite ends of the parts, one of the 10 cooperative pairs being angularly disposed to the other, the parts having apertured faces contactable to form a seal between the parts, a headed bolt fixedly mounted in the conduit part to have its stem project through one of the slots, a bolt 15 pivoted on the conduit part and swingable to extend its stem through the other cooperative slot, and nut means threaded on the pivoted bolt for applying pressure to the slotted coupling part against the fulcrum provided by the head on the fixed bolt whereby the parts are drawn together to 20 make a tight joint, said bolts being engaged with either of the cooperative pairs of slots to 25 vary the angular position of the form relative to the conduit.

2. In a hosiery drying structure, a coupling device for facilitating the rapid attachment and detachment to and from a heat supplying conduit of a hosiery drying form having a base flange normally intended to be directly attached to a conduit, comprising a pair of elongated coupling parts, one of the parts being permanently fastened to the wall of the conduit with its longitudinal center line parallel to the axis of the conduit and the other part adapted to be permanently secured to the flange and including a pair of open ended slots at each end thereof arranged to provide cooperative pairs at opposite ends of the parts, one of the cooperative pairs being substantially located along the longitudinal center line of the parts and the other cooperative pair being angularly disposed thereto, the parts having apertured faces contactable to form a seal between the parts, a headed bolt fixedly mounted in the conduit part to have its stem project through one of the slots at one end of the slotted part, a bolt pivoted on the conduit part and swingable to extend its stem through the other cooperative slot of the pair, and nut means threaded on the pivoted bolt for applying pressure to the slotted coupling part against the fulcrum provided by the head on the fixed bolt whereby the parts are drawn together to make a tight joint, the bolts being insertable through either of the cooperative pairs of slots to thereby vary the position of the form relative to the conduit.
